UNITED STATES PATENT OFFICE.

JOSEPH LEINER, OF WHEELING, WEST VIRGINIA, ASSIGNOR OF ONE-HALF TO JOSEPH F. PAULL, OF WHEELING, WEST VIRGINIA.

COMBINED SASH ACTUATING DEVICE AND LOCK.

1,101,861.

Specification of Letters Patent. Patented June 30, 1914.

Application filed August 2, 1913. Serial No. 782,678.

To all whom it may concern:

Be it known that I, JOSEPH LEINER, a citizen of the United States, residing at Wheeling, in the county of Ohio and State of West Virginia, have invented a new and useful Improvement in Combined Sash Actuating Devices and Locks, of which the following is a full, clear, and exact description, reference being had to the accompanying drawings, forming part of this specification, in which—

Figure 1 is a front elevation, looking from the inside of a window frame and sash embodying my invention; Fig. 2 is a section on the line II—II of Fig. 1; Fig. 3 is a detail view of a portion of one of the actuating devices; Fig. 4 is a section on the line IV—IV of Fig. 1, showing the lower sash in its raised position; Fig. 5 is a detail view of a portion of one of the actuating chains and nut; Fig. 6 is a view generally similar to Fig. 3, but showing the parts in a different position and also showing a modified form of knob or button; and Fig. 7 is a sectional detail view showing the knob or button of Fig. 6.

My invention has relation to a combined sash-actuating device and lock, and is designed to provide a simple and efficient device of this character which will be positive in its action; which can be operated only from the inside; and which will lock the sash either wholly open or wholly closed, or in any desired partially open position.

The nature of my invention will be best understood by reference to the accompanying drawings, in which I have shown a preferred embodiment thereof and which will now be described, it being premised, however, that various changes can be made in the details of construction and arrangement of the parts, without departing from the spirit and scope of my invention as defined in the appended claims.

In these drawings, the numeral 2 designates a window frame, 3 the upper sash mounted to slide therein in the usual manner, and 4 the lower sash also of the usual sliding form.

5 designates chains which are connected at their lower ends to the lower portion of the lower sash 4, one at each side. These chains are of lazy-tong construction, and preferably consist each of a series of double outer links 6, and single inner links 7.

The three upper links of each chain are attached by pivots 8 to two traveling nuts 9, which are mounted upon the threaded portion of a shaft or spindle 10. The two outer links at the upper end of each chain are connected to one of these nuts and the single central link is connected to the other nut. The shaft 10 is mounted in suitable bearings 11 in the window frame, and the portion thereof engaged by the nuts has a double thread 12 and 13, the two threads being of opposite hand. The frame is recessed, as shown at 2^a, in Fig. 4, to receive the threaded portion of the shaft, together with the nuts, and the edge of the sash is recessed or 7^a hollowed out, as shown at 14, to give sufficient clearance for the chains to work freely. I also preferably provide the upper sash 3 with similar chains 15, connected at their lower ends to the lower portion of the sash 7^a and at their upper ends to the shafts or spindles 16, which are similar to the shafts or spindles 10. Each of the four spindles is provided at its outer end with a knob or button 17, by means of which the shaft or 80 spindle can be rotated.

The operation will be readily understood. By turning the two shafts or spindles to which the chains attached to one of the sashes are connected, the nuts 9 are caused to move either toward or away from each other on the double threads 12 and 13. When the nuts are brought together in the position shown in Fig. 3, the lazy-tong chains will thereby be extended to their full length and 90 the sashes are in their closed positions. When the shafts or spindles are turned in the reverse direction, the nuts 9 separate, as shown in Fig. 6, and the lazy-tong chains are contracted, thereby, in the case of the lower sash, drawing it upwardly, and in the case of the upper sash, forcing it downwardly to open position.

In order to increase the speed of operation, without unduly increasing the pitch of the threads 12 and 13, I may employ knobs or buttons, such as shown in Figs. 6 and 7. In this form, the pinion 18 is secured to the outer end of the shaft or spindle, and is engaged by a plurality of concentrically 100 mounted pinions 19, journaled on studs or pins 20, carried by a suitable plate 21, which is fixed to the window frame. These intermediate pinions 19 are engaged by the internal rim gear 22, on the knob or button 110

proper 23. By rotating this knob or button, the series of pinions 19 are rotated in unison, thereby rotating the pinion 18 and the shaft or spindle.

5 The advantages of my invention will be apparent, since it provides a very simple and positive device for both actuating and locking the sashes. The device obviates the necessity for a box construction of the frame, such as is required with cords and pulleys; it can be applied at comparatively low cost, and it effectively prevents the sashes being operated from the outside.

I claim:

15 1. A window sash actuating and locking device, comprising a window frame having guides for a window sash, a window sash movably mounted in said guides, a lazy-tong chain in each guide attached to a sash at one end, operating shafts in the frame, one of said shafts extending into each guide, and

operating connections between the other end of each lazy-tong chain and its respective operating shaft, said connections being within the guides in the frame; substantially as 25 described.

2. The combination with a sliding window sash and its frame, of lazy-tong chains connected to said sash at one end portion, separate nuts connected to the other end of 30 each chain, shafts or spindles mounted in the window frame and having double thread portions engaged by said nuts, and actuating knobs or buttons for the shafts or spindles, substantially as described. 35

In testimony whereof, I have hereunto set my hand.

JOSEPH LEINER.
